(57) **CLAIM**

The ornamental design for a “connector of artificial bait for fishing gear,” as shown and described.

DESCRIPTION

FIG. 1 is a perspective view of connector of artificial bait for fishing gear showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof;

FIG. 7 is a bottom view thereof; and,

FIG. 8 is a reference view thereof.

The broken lines illustrating fishing gut and fishing bait in FIG. 8 are used for environmental purposes only and form no part of the claimed design.
